UNITED STATES PATENT OFFICE.

WILLIAM MCKISSICK, OF CARLISLE, IOWA.

STARTING DEVICE.

959,153.

Specification of Letters Patent. Patented May 24, 1910.

Application filed January 10, 1910. Serial No. 537,334.

To all whom it may concern:

Be it known that I, WILLIAM MCKISSICK, a citizen of the United States, residing at Carlisle, in the county of Warren and State of Iowa, have invented a new and useful Starting Device, of which the following is a specification.

This invention relates to starting devices for internal combustion engines characterized by a spring motor, the spring being wound up from the engine while the latter is in motion. Initial starting of the engine is effected manually, after which a device for winding up the spring is thrown in gear with the engine shaft.

It is the object of the present invention to provide a device of the kind stated which is simple in construction, and thoroughly reliable in operation, and also to provide means for automatically throwing the spring winding means out of gear at the proper time to prevent overwinding, and furthermore, to automatically throw said means into gear after each starting, so that the spring may be again wound up, and ready for the next starting of the engine.

With these objects in view, the invention consists in a novel construction and arrangement of parts to be hereinafter described and claimed, and in order that the invention may be fully understood, reference is had to the accompanying drawings, in which—

Figure 1 is a plan view of the device. Fig. 2 is an elevation of the mechanism for locking the spring. Fig. 3 is a longitudinal section on the line 3—3 of Fig. 1. Fig. 4 is a transverse section on the line 4—4 of Fig. 1.

The invention may be applied to any internal combustion engine, either stationary or portable, the drawing showing it applied to the engine of an automobile, a portion of the frame of the latter being indicated at 5. A fragment of the engine cylinder is shown at 6, and the crank shaft at 7. The crank shaft is fitted with the usual starting hand crank 8.

On the frame 5 is mounted a casing 9 which incloses a spring 10 coiled around a shaft 11, one end of the spring being made fast to the casing, and the other end to the shaft, so that upon winding up the spring, and releasing the shaft, the latter will be rotated. The shaft 11 is supported in suitable bearings carried by the frame of the

machine. On the shaft 11 is made fast a ratchet disk 12 which is engageable by a pivoted pawl 13, mounted on the frame 5, this pawl and ratchet mechanism being provided for locking the shaft 11. The edge of the pawl 13 is formed with a shoulder 14 which is engageable by one end of a lever 15 pivoted at 16 to the frame 5. The other end of the lever is engageable by a stem 17, which stem upon being disengaged from the lever, releases the pawl 13 so that the latter may swing away from the teeth of the ratchet disk 12 thus releasing said ratchet disk, and unlocking the shaft 11 so that it may be rotated by the spring 10. The stem 17 may be connected to any suitable actuating mechanism extending to the driver's seat so as to be within easy reach.

The herein described spring motor is employed for starting the engine, the shaft 11 of said motor being operatively connected to the crank shaft 7. The drawings show meshing spur gears 18 and 19, the former being on the shaft 11 and the latter on the shaft 7. A friction gearing, a sprocket and chain or any other suitable form of gearing may be substituted for the spur gearing shown. The gear 19 is loose on the shaft 7, a suitable clutch mechanism 20 being provided for locking said gear to said shaft. A lever or other device for throwing the clutch extends to the driver's seat. The gear 18 is fast on the shaft 11, in view of which it will be evident that the rotation of said shaft is transmitted to the shaft 7 when the gear 19 is locked thereto.

In order that the spring 10 may be wound up from the crank shaft 7, the following gearing is provided: On the shaft 11 is fast a miter gear 21 which is in mesh with a similar gear 22 on a shaft 23 extending transversely of the crank shaft 7. On the shaft 23 is also fast a worm wheel 24 adapted to mesh with a worm 25 fast on the crank shaft 7. The shaft 23 is mounted for swinging movement toward and from the crank shaft 7 so that the worm wheel 24 may be thrown in gear with the worm 25, or disengaged therefrom. When in gear, the motion of the crank shaft is transmitted to the shaft 23, and from the latter shaft to the shaft 11 through the gears 21 and 22, the gears being so arranged that the shaft 11 will be rotated in a direction to wind up the spring 10.

The shaft 23 is supported in a bearing 26 having an arm 27 which extends around the gear 22 and is pivotally mounted on the shaft 11. By thus mounting the bearing, 5 the shaft 23 may be swung as herein described.

The worm wheel 24 is mounted on that end of the shaft 23 adjacent to the free end of the bearing 26, and this end of the shaft 10 is formed with a screw 28 which is threaded through a nut 29 working between guides 30 mounted on a portion 31 of the frame of the machine, said nut traveling back and forth between the guides when the shaft 23 is rotated. The screw 28 causes the nut to travel 15 as stated, the guides 30 preventing rotation of the nut. The opposite faces of the guides 30 are formed with a groove 32, and the opposite sides of the nut are formed with 20 tongues 33 extending into said grooves. The guides 30 are located on one side of the crank shaft 11, and the grooves 32 are inclined in the direction of said shaft, so that when the nut 29 is traveling toward the crank shaft, 25 the shaft 23 will swing downwardly in the direction of the crank shaft, to engage the worm wheel 24 with the worm 25. When the nut 29 travels in the opposite direction, the shaft 23 is elevated, and the worm wheel 30 is then disengaged from the worm. The groove 32 forms an inclined shoulder 34 against which the tongues 33 are pressed by 35 a flat spring 35 secured at one end to a bottom portion 36 connecting the guides 30. The spring 35 is of sufficient strength to hold the shaft 23 and the parts carried thereby in elevated position when the nut 29 has taken the position in which the worm wheel 24 is disconnected from the worm 25. 40 In operation, the initial starting of the crank shaft 7 is effected manually in the usual manner by means of the hand crank 8. The shaft 11 will also be released so that the spring 10 may unwind. The nut 29 is so positioned on the screw 28 that the worm wheel 24 is now in mesh with the worm 25, 45 in order that the spring 10 may be wound up when the engine has started. The winding gear continues to operate until the spring 50 35 and nut 29 have elevated the shaft 23 to disengage the worm wheel from the worm. The parts will be so designed and dimensioned that this takes place when the spring has been wound to the proper tension, thus 55 preventing overwinding. The lever 15 is released so that the pawl and ratchet mechanism will automatically lock the shaft 11. The spring now being wound up, the device is ready to start the engine after it has 60 stopped and it is desired to again start the same. This is effected by releasing the shaft 11 in the manner already described and by locking the gear 19 to the crank shaft 7 by means of the clutch 20, the motion of the 65 shaft 11 being thus transmitted to the crank

shaft through the gears 18 and 19. This motion of the shaft 11 is also transmitted by the gears 21 and 22 to the shaft 23, the latter shaft turning in a direction to cause the nut 29 to travel down the inclined shoulder 34 toward the crank shaft, whereby the 70 shaft 23 is lowered, and the worm wheel 24 is again engaged with the worm 25. The spring 10 is now again wound up, and the winding mechanism is disconnected from 75 the crank shaft at the proper time in the manner already described. The spring 35 is made fast at its end which is nearest the shaft 7, and the portion 36 is spaced a sufficient distance from the shoulder in order 80 that the nut 29 may drop when it reaches this part of the spring, and then lower the shaft 23 sufficiently to engage the worm wheel with the worm. The spring has sufficient strength to lift the shaft and disengage the worm wheel and worm when the 85 direction of travel of the nut is reversed and it reaches the free portion of the spring, the latter then suddenly throwing the shaft upwardly so as to quickly disengage the worm 90 wheel and worm.

The device herein described is simple in construction, and highly efficient in operation. It can be readily applied to any internal combustion engine, either stationary 95 or portable, without altering or modifying the structure thereof.

The preferred embodiment of the invention has been shown and described, but it is to be understood that various changes in the 100 structural details may be resorted to without departure from the invention.

What is claimed is:—

1. In a starting device for internal combustion engines, the combination with the 105 engine shaft; of a spring motor; a driving connection between the motor and the shaft; a clutch in said connection; a winding device for the spring; a gearing between said winding device and the shaft; said gearing 110 including a worm on the engine shaft, and a worm wheel; a support for the worm wheel shaft mounted for swinging movement toward and from the worm to engage said worm wheel with the worm, and to disengage the same; and means for swinging said support.

2. In a starting device of internal combustion engines, the combination with the engine shaft; of a spring motor; a driving 120 connection between the motor and the shaft; a clutch in said connection; a winding device for the spring; a gearing between said winding device and the engine shaft, said gearing including a worm on the shaft, and 125 a worm wheel in mesh therewith; a shaft carrying the worm wheel; a support for the shaft mounted for swinging movement toward and from the worm to engage the disengage the worm wheel; a screw on the 130

- worm wheel shaft; a traveling nut threaded on the screw; and a guide for the nut inclined in a direction to throw the worm wheel shaft support toward and from the worm.
3. In a starting device for internal combustion engines, the combination with the engine shaft; of a spring motor; a driving connection between the motor and the shaft; a clutch in said connection; a winding device for the spring; a gearing between said winding device and the shaft; said gearing including a worm on the shaft, and a worm wheel in mesh therewith; a shaft carrying the worm wheel; a support for the worm wheel shaft pivotally mounted at one of its ends to swing toward and from the worm; a screw on that end of the last mentioned shaft which is adjacent to the free end of the swinging support; a traveling nut threaded on the screw; and a guide for the nut inclined in a direction to swing the worm wheel shaft support toward and from the worm.
4. In a starting device for internal combustion engines, the combination with the engine shaft; of a spring motor; a driving connection between the motor and the shaft; a clutch in said connection; a winding device for the spring; a gearing between said winding device and the engine shafts, said gearing including a worm on the shaft and a worm wheel in mesh therewith; a shaft carrying the worm wheel; a support for the worm wheel shaft mounted to swing toward and from the worm to engage and disengage the worm wheel; a screw on the worm wheel shaft; a traveling nut threaded on the screw; guides between which the nut is mounted, said guides being formed with shoulders inclined in the direction of the worm; tongues on the nut in contact with the shoul-
- ders; and yielding means for holding said tongues to the shoulder.
5. In a starting device for internal combustion engines, the combination with the engine shaft; of a spring motor; a driving connection between the motor and the shaft; a clutch in said connection; a winding device for the spring; a gearing between said winding device and the shaft; said gearing including a worm on the engine shaft, and a worm wheel; a support for the worm wheel shaft mounted for swinging movement toward and from the worm to engage said worm wheel with the worm, and to disengage the same; and automatically operating means for swinging said support.
6. In a starting device for internal combustion engines, the combination with the engine shaft; of a spring motor; a driving connection between the motor and the shaft; a clutch in said connection; a winding device for the spring; a gearing between said winding device and the engine shaft, said gearing including a worm on the shaft, and a worm wheel in mesh therewith; a shaft carrying the worm wheel; a support for the shaft mounted for swinging movement toward and from the worm to engage and disengage the worm wheel; a screw on the worm wheel shaft; a traveling nut threaded on the screw; and means for guiding the nut to travel in a direction to throw the worm wheel shaft support toward and from the worm.

In testimony that I claim the foregoing as my own, I have hereto affixed my signature in the presence of two witnesses.

WILLIAM MCKISSICK.
